FLUID HEAT EXCHANGER FOR AIR CONDITIONING AND REFRIGERATION SYSTEMS AND THE LIKE

Raymond A. Lo Turco, Wexford, Pa., assignor to
Frick Company, Waynesboro, Pa., a corporation of
Pennsylvania

Filed Sept. 1, 1967, Ser. No. 8,456

Term of patent 14 years

(Cl. D23—153)

FIG. 1

FIG. 2

FIG. 1 is a perspective view of the fluid heat exchanger for air conditioning and refrigeration systems and the like according to this invention, and

FIG. 2 is a top plan view of the fluid heat exchanger for air conditioning and refrigeration systems and the like as shown in FIG. 1.

The hatched shading throughout the figures is representative of a mesh pattern and is understood to be continuous throughout the areas so shaded.

I claim:

The ornamental design for a fluid heat exchanger for air conditioning and refrigeration systems and the like, as shown and described.
